UNITED STATES PATENT OFFICE.

OWEN H. JONES, OF HARTFORD, CONNECTICUT, ASSIGNOR OF ONE-HALF
TO FRANK C. SMITH, OF NEW YORK, N. Y.

CAR-VENTILATOR.

SPECIFICATION forming part of Letters Patent No. 293,578, dated February 12, 1884,

Application filed February 15, 1883. (No model.)

To all whom it may concern:

Be it known that I, OWEN H. JONES, of Hartford, in the county of Hartford and State of Connecticut, have invented new and useful 5 Improvements in Car-Ventilators, of which the following is a specification, reference being had to the accompanying drawings, in which—like letters of reference indicating like parts—

10 Figure 1 is a side view of a section of a car-floor with my device attached thereto; and Fig. 2 is a sectional view of the same, illustrating the detail of construction.

Heretofore various devices have been used 15 as car-ventilators, many of which are objectionable, because of being complicated, and many do not accomplish the desired result—to wit, the thorough and complete ventilation of the car; and the object of my invention is to 20 accomplish the thorough ventilation of a car with a simple and cheap apparatus.

My invention consists in providing a car 25 with a ventilator tube or box having an exit-tube pivoted to turn and present the opening in a direction opposite to that in which the car is moving, the interior of said box being suitably connected with the interior of the car.

In the drawings, *a* represents a section of car-floor; *b*, an air-box; *c*, an exit-tube; *d*, a 30 vane; *e*, tubes connecting the interior of the car with the air-box; *f*, registers in the floor; *g*, cross-pieces in the air-box wherein the rod *h* has bearings, and *h* a pivotal rod holding the exit-tube in position, while allowing it to turn 35 in any direction. The motion of the car causes the vane *d* to present its edge in the direction in which the car is moving, thus causing the

opening in the tube *c* to be turned in a direction opposite to that in which the car moves. The current of air formed around the orifice 40 in the tube by the rapidly-moving train exhausts the air from the tube and box, and thus from the interior of the car.

The ventilation may be controlled by opening or closing the registers *f*. I prefer to connect the exhaust-tubes with the interior of the car at the bottom, where the body of cold and impure air is found. They may, however, be connected at other points, if desired.

The tube *c* may be secured to the box *b* with 50 the well-known collar-connection, which permits it to turn. I prefer, however, to hold this tube in position by the rod *h*, passing from a bearing in the tube to one or more cross-pieces, *g*, in the interior of the air-box. 55

Having therefore described my invention, what I claim as new, and desire to secure by Letters Patent, is—

1. The combination of air-box *b* with air-pipes *e* *e*, said pipes being provided with registers, and said box being provided with an exit-tube adapted to revolve on the air-box, and provided with a means to turn the opening in a direction opposite that in which the car is moving, substantially as shown. 60
2. As a car-ventilator, box *b*, pipes *e* *e*, tube *c*, having vane *d*, and a rod, *h*, all constructed and operating in combination substantially as shown. 65

OWEN H. JONES.
